UNITED STATES PATENT OFFICE

162,267

SUBMARINE

Walter Wiggins, Jr., Kenilworth, Md.

Application November 3, 1950, Serial No. 12,828

Term of patent 14 years

(Cl. D71—1)

To all whom it may concern:

Be it known that I, Walter Wiggins, Jr., a citizen of the United States, residing at Kenilworth, Beaver Heights, in the county of Prince Georges and State of Maryland, have invented a new, original, and ornamental Design for a Submarine, of which the following is a specification, reference being had to the accompanying drawing, forming part thereof.

Figure 1 is a side elevational view of a submarine, showing my new design;

Figure 2 is a top plan view thereof;

Figure 3 is an underside plan view;

Figure 4 is a front end view; and

Figure 5 is a rear end view of the same.

I claim:

The ornamental design for a submarine, as shown.

WALTER WIGGINS, JR.
